UNITED STATES PATENT OFFICE.

CLYDE J. COLEMAN, OF NEW YORK, N. Y., ASSIGNOR TO CONRAD HUBERT, OF NEW YORK, N. Y.

NEEDLE-VALVE.

1,038,527.

Specification of Letters Patent. Patented Sept. 17, 1912.

Application filed September 12, 1907, Serial No. 392,575. Renewed February 24, 1912. Serial No. 679,766.

To all whom it may concern:

Be it known that I, CLYDE J. COLEMAN, a citizen of the United States, residing at the borough of Manhattan, city of New York, in the county of New York and State of New York, have invented a certain new and useful Improvement in Needle-Valves, of which the following is a specification, reference being had therein to the accompanying drawings, forming part thereof.

My invention relates to valves and relates particularly to such valves as are adapted for use on portable tanks or storage reservoirs for containing gases under high pressure for illuminating purposes, such, for example, as acetylene gas. One of the common uses of such portable gas tanks is upon automobiles, for supplying illuminant to the lamps thereof. For such uses the gas storage tank is necessarily comparatively small, to save weight and space, and must therefore be charged to an extremely high pressure to supply sufficient illuminant for the desired length of time.

The smallness of the storage reservoir and the high initial pressure of the stored gas introduce the difficulty in the use of the gas that the pressure falls rapidly, necessitating very frequent adjustments of the valve to preserve the lamp flame of proper size; and the chief object of my present invention is to overcome this inconvenience.

Other objects and advantages will appear from the following description.

My invention includes means controlled by the high pressure fluid for controlling the amount of fluid supplied to the point of use.

My invention also includes various details of construction and combinations of parts.

I will now describe the embodiment of my invention illustrated in the accompanying drawing, which shows a longitudinal central section of the complete valve, together with portions of contiguous parts, and will thereafter point out my invention in claims.

The illustrated embodiment of my invention comprises a plug member 1, for attachment to a source of fluid under pressure, for example, a container 16, a portion only of which is shown, and a valve-carrying cap member 2, shown as united by screw threads to the plug 1. The plug 1 has a longitudi-

nal service-passage 3 which communicates, through the valve mechanism hereinafter described, with a transverse service-passage 4 provided in the member 2, the direction of flow of fluid when used being as indicated by the arrows. A service-duct 5, leading to the point of use and shown as broken away, is connected to a nipple formed on the member 2 by an ordinary screw connector-ring 6 and forms a continuation of the service-passage 4.

Delivery of fluid through passage 4 and duct 5 is automatically controlled by a compensating valve mechanism which in turn is controlled by the pressure of the high pressure fluid in the container 16 and passage 3. Such mechanism comprises a diaphragm 7 clamped between the members 1 and 2 and made fluid-tight by a packing-ring 8 which may be of aluminum. The member 1 is cup-shaped or hollowed out at its top to form a chamber 9 constituting a pressure-chamber or diaphragm-chamber, of which the diaphragm forms one wall, and the member 2 is also shown as slightly hollowed out or cup-shaped and in coöperation with the packing-ring 8 forms a free space or receiving-chamber 10 above the diaphragm. The passage 3 forms an inlet for the pressure-chamber 9 and an outlet therefor is formed in a valve-seat 11 carried at the center of the diaphragm. The valve-seat 11 is shown as secured to the diaphragm by a nut 12, and the joint is made fluid-tight by a washer 13, the valve-seat being in the form of a tubular stud.

A tapered valve proper or needle valve 14 is supported in the member 2 and coacts with the valve-seat 11, which has a flaring opening for receiving the tapered portion of the valve. The valve 14 has a threaded engagement with the member 2 and has a handle portion extending to the outside, through an ordinary packing gland as shown, for manual adjustment of the valve relatively to its seat. The nut 12 extends upward some distance from the diaphragm in the form of a tube or sleeve and is guided at its uppermost portion on the shank or stem portion of the needle valve 14, so as to assure at all times a proper seating of the valve, as otherwise the diaphragm might at times buckle or twist and prevent proper coaction or coöperation of the valve and valve-seat. The bore of the tubular nut 110

12 is reduced at its upper portion for guidance on the valve and is provided with counterbores for exit of fluid passing the valve. The upwardly-extending portion of 5 the nut 12 is loosely received in a bore 15 in the member 2 and which communicates with the service-bore 4 therein.

In the operation of the device the valve may be opened more or less or completely 10 closed off at any time by adjustment of the valve proper 14 in the usual manner. When the valve is firmly closed the head of the stud 11 forming the valve-seat will rest against the bottom of the pressure-chamber 15 9 and thereby prevent a possible disruptive strain from being placed on the diaphragm by too greatly tightening the valve 14. We will suppose that the device is in use on a reservoir of comparatively small dimensions 20 and containing fluid under high pressure initially and that the valve 14 is firmly closed against its seat. As the valve 14 is moved in its opening direction, by unscrewing, the valve-seat 11 will follow the opening movement of the valve for a certain distance and until, the tension of the diaphragm becomes equal to the pressure of the fluid in the pressure-chamber 9, the valve of course remaining seated or "closed" up to this point. 30 Further opening movement of the valve 14 will separate it from its seat and permit flow of fluid from passage 3 out through service-duct 5 to point of use. The valve may now be opened to a greater or less extent to permit more or less fluid to pass as desired. When the valve has once been adjusted no further adjustment or attention will be necessary, as the initial adjustment serves also as a final adjustment, even 40 though the pressure of the fluid in the container has been reduced by continued usage. However, if the size of the valve-opening remained the same, less fluid would pass therethrough and the light would accordingly grow dim as the pressure in the container became reduced from usage of fluid therefrom. This tendency is offset by the compensating action of the valve mechanism. As the pressure of fluid in the container 45 becomes reduced the pressure of fluid in the pressure-chamber 9 is correspondingly less and failing to longer balance the tension of the diaphragm, an inward movement of the diaphragm takes place, separating the valve-seat 11 more widely from the valve 14, thus compensating for the reduced pressure by providing a larger opening, whereby substantially the same quantity of fluid is delivered to the point of use 55 irrespective of whether the pressure in the container is high or low.

In the drawing the device is indicated as in use, the outlet-valve 14 being represented as open and the diaphragm 7 as bent outward by pressure of fluid in the pressure-chamber 9 and controlling the escape of the fluid in accordance with the amount of pressure in the container 16 as explained above. 65

It is obvious that various modifications may be made in the construction shown and 70 above particularly described within the principle and scope of my invention.

I claim:

1. A valve mechanism comprising a pressure-chamber provided with an inlet and 75 an outlet, a diaphragm forming a wall of the pressure-chamber, a valve-seat carried by the diaphragm, an outlet valve coactive with the valve-seat and having a stem extending outward, and a guide for the valve-seat carried by the diaphragm and guided by the valve stem. 80

2. A valve mechanism comprising a pressure-chamber provided with an inlet and an outlet, a diaphragm forming a wall of 85 the pressure-chamber, a valve-seat carried by the diaphragm, an outlet-valve coactive with the valve-seat from the outside of the pressure-chamber, the co-action of the valve and its seat being controlled by the diaphragm, and means for imparting opening and closing movements to the valve independently of the diaphragm, the valve-seat being adapted to rest on the bottom of the pressure-chamber when the valve is firmly 90 closed by said means, whereby the diaphragm is relieved of excessive strain. 95

3. A valve mechanism comprising a pressure chamber provided with an inlet and an outlet, a diaphragm forming a wall of the 100 pressure chamber, a valve seat carried by the diaphragm, an outlet valve coactive with the valve seat from the outside of the pressure chamber and having a stem extending outward, the coaction of the valve 105 and its seat being controlled by the diaphragm, and a guide for the valve seat carried by the diaphragm and guided by the valve stem, the valve stem being manually operable for imparting opening and closing 110 movements to the valve independently of the diaphragm and the valve seat being adapted to rest on the bottom of the pressure chamber when the valve is firmly closed by manual actuation. 115

In testimony whereof I affix my signature in presence of two witnesses.

CLYDE J. COLEMAN.
